UNITED STATES PATENT OFFICE.

GEORGE W. BERGLUND, OF BROOKLYN, NEW YORK, ASSIGNOR TO THE STA-STRAIT COMPANY, OF NEW YORK, N. Y., A CORPORATION OF NEW YORK.

DISPLAY DEVICE FOR JEWELRY, ETC.

Application filed February 18, 1921. Serial No. 445,944.

To all whom it may concern:

Be it known that I, GEORGE W. BERGLUND, a citizen of the United States, residing in the borough of Brooklyn, of the city of New York, in the State of New York, have invented certain new and useful Improvements in Display Devices for Jewelry, etc., of which the following is a specification, reference being had to the accompanying drawing, forming a part hereof.

The purpose of this invention is to provide a device for the convenient display and sale of button insignia, that is insignia of fraternal orders, etc., intended to be worn in the lapel buttonholes of men's garments and other jewelry or articles of similar character, formed with a head which shows the symbol or pattern or design, a foot, and a connecting shank. Articles of this general character are commonly applied to small cards which are slotted to receive each the foot of the article and such cards with the buttons applied thereto are placed, in the retail store, in a tray or basket or drawer, different specific articles together and when a customer desires to purchase a particular button or buttons the salesman places the tray or drawer or basket on the show case or puts a handful of the miscellaneous buttons on the showcase. The salesman and the customer then sort out and finger the articles until a desired button is found. This usual procedure in the sale of such articles consumes considerable time and involves much handling of the articles with a consequent soiling of the cards and oftentimes tarnishing and scratching of the buttons. In accordance with this invention there is provided a holder of convenient shape for handling, which is adapted to receive and hold in view a number of assorted button-bearing cards, so that when a customer desires to make a purchase the salesman can place before him the holder and the customer can at a glance select the desired button, which can then be removed, with its card, from the holder, delivered to the customer, and replaced, in the holder, by the salesman, by another button taken from assorted stock. The improved display device is simple in character, inexpensive to manufacture, highly efficient, and satisfactory in every way to the user. The invention will be explained more fully

hereinafter with reference to the accompanying drawing in which it is illustrated and in which—

Figure 1 is a face view of a holder or of a portion of a holder, with several button-bearing cards in position and others removed to show details of construction.

Figure 2 is a view of the same in transverse section.

The holder, preferably made of thin metal, is trough-like in section, having a depressed central portion *a*, at the upper edges of which are outwardly turned lateral flanges *f*. At the outer edges of these flanges *f* are inturned flanges *b* of somewhat less width so that a portion of each flange *f* is left as a shoulder extending inward beyond the inner edge of flange *b*. Between the flanges *f* and *b* is left a space sufficient to receive the edges of the slotted cards *c*, each of which supports in usual manner a button *d*. The latter is of usual character, having a head which bears the symbol or design, a foot, and a connecting shank. The card *c*, bearing the button *d*, being slightly bent, has its opposite edges engaged by the inturned flanges *b* and the trough-like body *a* of the holder supports the card and its button with the foot out of contact with the holder, so that the foot is not scratched. In order to insert a card in the holder, one edge is slipped into the space between a flange *b* and a flange *f* on one side of the holder, and the card is sprung upward at its mid-portion so that its free edge may be inserted into the space between the flanges *b* and *f* on the other side of the holder, the shoulder formed as above described, serving to guide the edge of the card into this space. As the card is allowed to spring back into flat condition its edges will extend into the spaces between the flanges far enough to ensure the card being firmly held. Any card, with its button, can be disengaged readily from the holder, since the flanges receive the edges of the card freely, and the place of any card removed can be filled at once by another card and button. Furthermore, the cards can be slipped lengthwise of the holder so as to permit the cards to be arranged as desired on the holder and to be slipped into place or removed at the end of the holder, if so desired. If desired, the bottom of the trough-like body *a*

can be provided with slots *e*, by means of which the holder can be hung upon pins provided for the purpose.

I claim as my invention:

5 As a new article of manufacture, a display device adapted to support button bearing cards comprising a trough-like holder formed of a single piece of sheet material having a flat bottom of substantial width and having flaring sides, outwardly extending flanges at the upper edges of the sides adapted to support the edges of the cards

and means for retaining the cards consisting of flanges extending inward from the outer edges of the supporting flanges of less width than the supporting flanges and separated therefrom by a space adapted to receive the edge of a card, the flat bottom being of sufficient width to maintain the cards in horizontal position.

This specification signed this 16th day of February, A. D. 1921.

GEORGE W. BERGLUND.
